C. H. KIRBY

TROUSERS STRETCHER AND GREASER

Filed Oct. 20, 1923

UNITED STATES PATENT OFFICE.

CLYDE H. KIRBY, OF EVERTON, MISSOURI.

TROUSERS STRETCHER AND CREASER.

Application filed October 20, 1923. Serial No. 669,799.

To all whom it may concern:

Be it known that I, CLYDE H. KIRBY, a citizen of the United States, residing at Everton, in the county of Dade and State of Missouri, have invented certain new and useful Improvements in Trouser Stretchers and Creasers, of which the following is a specification.

This invention relates to improvements in trousers stretchers and creasers, and has for its object to provide a cheap, simple, and efficient device, by which a pair of trousers may be held and stretched, so that all of the wrinkles may be removed and a crease 15 pressed in the back and front of the leg portions.

The invention will be found extremely serviceable for maintaining the crease formed in trousers during the period when the same 20 are stored, and embodies construction whereby the device may be reduced to a compact form when not in use. Also, the device will remove objectionable bagging at the knees of the trousers and avoid glossing of 25 the trousers when creasing the same.

Another object of the invention is to provide means whereby the legs of a pair of trousers may be separately engaged for creasing and stretching the same.

Still another object is to provide a simple and improved means for spreading the trousers engaging clamp by means of which the trousers will be effectively stretched.

Other objects will appear as the nature of 35 the invention is better understood, and the same consists in the novel form, combination, and arrangement of parts hereinafter more fully described, shown in the accompanying drawings, and claimed.

In the drawings, wherein like reference characters indicate corresponding parts throughout the several views:

Figure 1 is a side elevational view of an apparatus constructed and arranged in accordance with the present invention, the apparatus being shown in service.

Figure 2 is an enlarged transverse sectional view taken substantially upon the line 2—2 of Figure 1.

Figure 3 is an enlarged fragmentary transverse sectional view, taken through one

of the trousers engaging clamps above one of the screw clamps, and

Figure 4 is a view of one of the trousers 55 engaging clamps in open position.

As seen in the drawings, the apparatus employs six bar like leaves 5 that are associated in units of three leaves each to form a pair of three part clamps, the leaves of each of which are permanently united by 60 means of hinges 6. This provides a construction by means of which the legs of a pair of trousers may be separately engaged, one leg of the trousers being disposed between the intermediate member of one clamp 65 and one of the outer members thereof, and the other leg of the trousers being engaged between said intermediate member and the other outer member of the clamp as shown in Figure 2. By means of this construction, 70 the trousers may be arranged in a very neat condition, so that each leg thereof will be properly disposed and held.

The leaves 5 are held in service by a screw clamp 7, any number of which may be employed. In the drawings, four of the screw clamps 7 are shown, and constitute a sufficient number to be ordinarily used. As shown each clamp is provided with a screw 75 80 threaded through a U-beam 9.

Associated with the trousers engaging clamps are a pair of spreading devices by means of which said clamps are yieldably separated for stretching the trousers engaged thereby. Each spreading device embodies a 85 pair of transversely extending bars 10, the opposite ends of which are connected in parallel spaced relation by means of transverse pins 11 and the bars 10 of each spreading device are arranged at opposite sides of the 90 clamp as shown clearly in Figure 2 and of greater length than the width of the trousers legs as shown clearly in Figure 1. The intermediate leaf 5 of one of the trousers engaging clamps is provided in its outer edge 95 with a pair of rigid hooks 12, one of which engages the cross pin 11 at one end of each of the spreading devices. The intermediate leaf of the other trousers engaging clamp is provided with a similar pair of hooks 13, 100 with which are engaged the inner ends of a pair of helical tension springs 14, which

have their outer ends engaged with hooks 15 provided upon the cross pins 11 at the other ends of the spreading devices. When arranging the apparatus for service, the leaves 5 of each three part trousers engaging clamp are spread, after which the trousers are folded and placed with the legs thereof separately engaged between the leaves. When the leaves of the clamps are engaged tightly over the trousers legs the clamps 7 are installed in service and the screws 8 are manipulated to exert a closing pressure on said leaves and on the intervening trousers legs. After the creased edges at one side of the trousers have been secured, the folded edges of the opposite side of the trousers are placed between the leaves 5 of the opposite trousers engaging clamps and the clamps 7 therefore are manipulated as above described with respect to the first pair. It will be understood that the opposite edges of both legs of the trousers are creased at the same time and separately held between the leaves of the trousers engaging clamps. After the two pairs of clamps have been secured, the spreading devices are installed, as shown in Figure 2, with the hooks 12 and 13 of the trousers engaging clamps respectively engaged with the pins at one end of each of the pairs of bars 10 and with the inner ends of the springs 14 that are connected to the other ends of said bars. In this position, the springs 14 exert a spreading action upon the trousers engaging clamp for stretching the trousers and removing creases therefrom between the edges of the same engaged by the clamps and the trousers may be suspended or hung away by any suitable means as generally indicated at 16 in Figure 1.

From the above description, it is believed that the construction and operation as well

as the advantages of the present invention will be readily understood and appreciated by those skilled in the art.

What I claim as new is:

1. An apparatus as characterized comprising a plurality of creasing leaves pivotally connected to provide a pair of trousers engaging clamps, the leaves of which open bookwise, a plurality of screw clamps for compressing said leaves upon each other, a pair of rigid hooks projecting outwardly from a leaf of each trousers engaging clamp, pairs of bars arranged at opposite sides of said trousers engaging clamps and extending transversely of the upper and lower ends of the latter, the bars of each pair being connected by transverse pins, one of said transverse pins of each pair of bars being engaged by one of said hooks, yieldable tension springs engaging the other hook and attached to the other cross pin of said pairs of bars whereby said trousers engaging clamps are yieldably separated or spread relative to each other.

2. An apparatus as characterized comprising a pair of trousers engaging clamps composed of a plurality of leaves hingedly connected to open bookwise, and spreading devices for said trousers engaging clamps, said spreading devices including pairs of transversely extending bars arranged at opposite sides of the clamps and connected in parallel spaced relation at their ends by means of transverse pins, tension springs connecting one of said clamps with the pins at one end of each of said bars, and hooks carried by the other clamp engaging the outer pin of said bars.

In testimony whereof I affix my signature.

CLYDE H. KIRBY.
